CLAIM

The ornamental design for a decompression needle cap and closure, as shown and described.

DESCRIPTION

FIG. 1 is a side view of the subject decompression needle cap and closure in the open position.

FIG. 2 is a top view of the subject decompression needle cap and closure in the open position.

FIG. 3 is a cross-sectional view of the subject decompression needle cap and closure taken in the direction of line 3-3 shown in FIG. 2.

FIG. 4 is a bottom view of the subject decompression needle cap and closure in the open position.

FIG. 5 is a cross-sectional view of the subject decompression needle cap and closure in the open position taken in the direction of line 5-5 shown in FIG. 2; and,

FIG. 6 is a top perspective view of the subject decompression needle cap and closure in the open position.

1 Claim, 6 Drawing Sheets
